CLAIM

The ornamental design for a body shaver cartridge, as shown and described.

DESCRIPTION

FIG. 1 is a top, front and left side perspective view of a body shaver cartridge, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion labeled "9" in FIG. 3.

The dot-dash broken line rectangle frames in FIGS. 3 and 9 define the boundary of an enlarged view and form no part of the claimed design.
